United States Patent Office.

MADISON BUELL AND WILLIAM WOOD LESLEY, OF NEW CASTLE,
DELAWARE.

Design No. 4,838, dated April 25, 1871.

DESIGN FOR THE SIDE OF A RAILWAY CAR.

The Schedule referred to in these Letters Patent and making part of the same.

We, MADISON BUELL and WILLIAM WOOD LESLEY, both of New Castle, county of New Castle, State of Delaware, have invented or produced a Design for the Side of a Railroad Car, of which the following is a specification.

In the accompanying drawing—

Figure 1 represents a side view of part of a railway car made in accordance with my design;

Figure 2, a sectional plan on the line 1 2, fig. 1; and

Figure 3, a vertical section on the line 3 4, fig. 1.

A A represent the openings in the side of the car for the reception of the sashes and blinds;

b b, the panels below these openings; and

D D, the pilasters between the windows.

These pilasters are edged with beadings e e, which

are continued over the arched tops of the windows and on each beading adjacent to the window is a strip, G, of the shape best observed in fig. 3.

Claim.

The design for the side of a railroad car, as described and shown.

In testimony whereof we have signed our names to this specification in the presence of two subscribing witnesses.

MADISON BUELL.
WM. WOOD LESLEY.
